CLAIM

The ornamental design for a wireless gateway, as shown and
described.

DESCRIPTION

FIG. 1 is a perspective view of a wireless gateway embodying
my design;

FIG. 2 is a right side elevational view thereof;

FIG. 3 is a top view thereof;

FIG. 4 is a front elevational view thereof;

FIG. 5 is a bottom view thereof;

FIG. 6 is a left side elevational view thereof; and,

FIG. 7 is a rear elevational view thereof.
